UNITED STATES PATENT OFFICE

2,321,057

METHOD OF PRINTING

Adolph Weiss, Brooklyn, N. Y., assignor, by mesne assignments, to Interchemical Corporation, New York, N. Y., a corporation of Ohio

Original application June 2, 1938, Serial No. 211,325. Divided and this application October 25, 1939, Serial No. 301,113

9 Claims. (Cl. 101—426)

This invention relates to methods of rotary intaglio printing. The subject-matter was initially presented in my application Serial No. 211,325, filed June 2, 1938 (now Patent No. 2,217,191, issued October 8, 1940), of which this is a division.

In conventional rotary intaglio printing, the length of the printing cylinder impression is equal to the peripheral length (i. e., circumference) of the printing cylinder. Thus, the diameter of the cylinder determines the length of the impression, and a different diameter printing cylinder is required for each length of impression desired.

Objects of this invention are to provide methods of making impressions greater or less than the peripheral length of the printing cylinder.

Other objects are to provide methods of varying the length of the impression without varying the peripheral length of the printing cylinder.

Further objects are to provide flexibility for meeting various industrial requirements with rotary intaglio printing.

Various additional objects will become evident from the following disclosure.

It will be understood that when I refer to "length of the printing cylinder impression" or "length of the impression," I mean the length of web which passes the printing point during one complete printing cycle; and this is regardless of whether or not the printed design occupies the entire length of the "impression," and regardless of whether the printing cycle involves one, more than one, or less than one rotation of the printing cylinder. Thus, "length of the impression" (or the like) should not be confused with the peripheral length of the printing cylinder.

Fig. 1 of the drawings is a diagrammatic view showing a rotary intaglio printing press with which the present invention may be carried out.

Fig. 2 is an enlarged scale elevation, partially in section, of a phase change coupling shown in Fig. 1. While this is a structural type of view, the figure is supplementary to diagrammatic Fig. 1. Accordingly the illustration of the coupling may be considered as diagrammatic in its relation to the machine as a whole.

Fig. 3 is a partially diagrammatic elevation of an adjustable cam that may be utilized in presses which carry out the present invention.

Figs. 4 to 12, inclusive, are diagrammatic views illustrating some of the variations in printing results that can be achieved by utilizing the present invention.

Reference will first be had to Figs. 1, 2, and 3. A web 145 passes from supply roll 170 over guide roller 171 and between printing cylinder 172 and pressure roller 174. Subsequent to the printing, the web passes between feed rollers 175 and 176, and is delivered between the blades 177 and 178 of cutting shears. Between the printing cylinder 172 and feed rollers 175, 176, the web may pass over two rollers 179 and 180, which are so arranged as to vary the distance which the web must travel in moving from the printing cylinder to the cutting shears. The axis of roller 179 is stationary, but roller 180 is rotatably mounted on a swinging frame 181 which is pivoted coaxially with roller 179. By swinging the frame 181 and locking it to a sector 182 by set screw 184, adjustment is made to vary the length of the travel of the web between the printing cylinder 172 and the cutting shears. This adjustment permits severing of the web at any selected point in the printing cylinder impression, so that printed slips may be made with the printing located in any desired zone of the slip. For continuous strip printing the shears may be omitted or rendered inactive.

The various driven elements of the press are mechanically connected together to be actuated from a single source of power indicated as an electric motor 185. To permit a clear and convenient diagrammatic showing of the operating relationship of the different parts, bevelled gears have been indicated in Fig. 1 of the drawings. However, in actual machine construction, it is preferable to so arrange the parts as to permit the use of spur gears or the like. As shown in the drawings, the motor drives shafts 186^a and 186^b, which are in effect a single shaft. By means of shaft 187, power is transmitted to the printing cylinder 172 to rotate it at predetermined speed, which may be the speed of the motor. A cam 188 (to be referred to later) is driven in coordination with the printing cylinder 172 by power transmitted to it through shaft 189, phase-change coupling 190, shaft 191, variable speed mechanism 192, and shaft 193, which is geared to the drive shaft. At least one of feed rollers 175 and 176 is driven in coordination with the printing cylinder 172, the driving power being transmitted from the drive shaft 186^b through shaft 194, variable speed mechanism 195, and shaft 196. The movable blade 177 of the web cutting shears is adapted to be actuated by cam 197, which is also driven in coordination with the printing cylinder 172. The power for driving the cam 197 is derived from the power shaft

186^b through shaft 198, variable speed mechanism 199, shaft 200, phase-changing coupling 201, and shaft 202.

Pressure roller 174 is rotatably mounted on a pivoted frame 203, which is adapted to be rocked by cam 188. When the inactive (or low) zone of cam 188 is in contact with roller 204, the pressure roller 174 holds the web 145 in contact with the printing cylinder 172. Accordingly, throughout the inactive zone of cam 188 the web is printed with any design which passes the printing zone of the printing cylinder 172. However, during the active (or high) zone of cam 188, the pressure roller 174 is elevated, with the result that the web is out of contact with the printing cylinder and no printing play takes place.

While the web is out of contact with the printing cylinder, it is, nevertheless, advanced by feed rollers 175, 176, which may be driven at the same peripheral speed as the speed of the printing cylinder 172. By means of variable speed mechanism 185, the peripheral speed of feed rollers 175, 176 may be adjusted to conform with the peripheral speed of different sizes of printing cylinders 172 which may be inserted into the machine. Variable speed mechanism 199 provides an adjustment so that the cutting shears may be set to operate at any desired frequency in relation to the cyclic operation of the machine; for example, the web may be severed into lengths corresponding to one, less than one, or more than one rotation of printing cylinder 172. Phase-change coupling 201 provides a means whereby the point of severance may be located on the web, though a similar location may be effected by adjusting the position of roller 180. Variable speed mechanism 192 permits the control cam 188 to be rotated at various cyclic rates in relation to the rotation of the printing cylinder 172. Also phase-change coupling 198 permits any inactive sector of cam 188 to be located in coordination with any selected peripheral zone of the printing cylinder 172.

The press may be so controlled that upon being set in operation, it automatically stops after one or more printing cycles (e. g., after printing and cutting one or more slips).

A cam 300 is shown as driven from drive shaft 186^a through shaft 301, variable speed mechanism 302, shaft 303, phase change coupling 304, shaft 305, and shaft 306. Thus cam 300 may be set at any phase with respect to the printing cylinder; and for each rotation of the printing cylinder, this cam may make one, more than one, or less than one rotation. Once each rotation, cam 300 elevates member 103' and stops the press. The starting and stopping of the press is effected by controlling motor 185 with a mechanical and electrical system associated with member 103'. This system will now be described.

Suitably insulated and mounted are movable contacts 150 and 152 which are spring biased away from stationary contacts 151 and 153 respectively. Pivotedly mounted as shown in a bell crank lever 154 having a vertical leg adapted to engage contact 152. A spring 154^a biases bell crank lever 154 with sufficient strength to overcome the bias of contact 152 and close the same when lever 154 is free to move. A shaft 155 has keyed or pinned thereto a bell crank lever 156. This lever is movable to close contact 150, but is biased in the opposite direction by spring 156^a.

Assume that the machine is in operation, with the printing cycle in progress. The electrical contacts are then in the positions shown, the circuit

to the motor 185 being maintained by relay R. The holding circuit for relay R is through connection 160, contact 150, contacts 153 and 152, and connection 161 and switch 164 to the line. At the 5 end of the printing cycle member 103' is raised by cam 300. This moves bell crank lever 154 and permits contacts 152, 153 to open. The opening of contacts 152, 153 breaks the holding circuit of relay R, allowing the relay to open and 10 stop driving motor 185. Thus the press stops with the member 103' in its uppermost position. Attached to member 103' is a latch-engaging hook 162 which moves upwardly with member 103', allowing latch 163 to advance so that its upper 15 portion engages the end of the horizontal arm of bell crank lever 156 when the press is stopped.

To restart the press, shaft 155 is moved clockwise in any suitable way, e. g. manually. In parent application Serial No. 211,325, filed June 2, 20 1938 (now Patent No. 2,217,191, issued October 8, 1940), I have shown means for moving shaft 155 clockwise (to start the press) upon extraction from the machine of a previously printed slip. Movement of shaft 155 clockwise, moves bell crank lever 156 clockwise. This closes contacts 150, 151 which complete the circuit to relay R, so that the relay operates and starts the driving motor 185. The movement of bell crank lever 156 also causes its horizontal arm to snap under latch 163 25 which is arranged to hold the bell crank lever in its operated position, thereby maintaining contacts 150, 151 closed as the press starts to operate. The initial movement of the press causes member 103' to descend, which allows bell crank lever 154 to rotate clockwise and close contacts 152, 153. This restores the original holding circuit for relay R, through connection 160, contact 150, contacts 153 and 152, connection 161, and switch 164. After contacts 152, 153 are closed, 30 hook 162 retracts latch 163 and permits bell crank lever 156 to return to the position shown and contacts 150, 151 to open.

When the machine cycle is completed, contacts 152, 153 are again opened and the machine, 45 stopped. If it is desired to operate the press continuously, switch 164 is shifted from contact 165 to contact 166, thus connecting the motor 185 for continuous operation.

Fig. 2 shows more clearly the diagrammatic 50 phase-change couplings 190, 201, and 304. The driving shaft of the coupling is keyed to a collar 205 and the driven shaft is keyed to an abutting collar 206. Set screw 207 secures collar 205 to the driven shaft for the transmission of power. 55 By loosening the set screw, the driven shaft can be rotated with respect to the driving shaft to change the operating phase of the part actuated from the driven shaft. To aid in making the adjustment, the contiguous ends of collars 205 and 206 may be provided with a scale and co-operating index as shown in the drawings.

The control cam 188 for elevating the pressure roller 174 may be of a suitable adjustable type. One of such type of adjustable cam is shown in 60 Fig. 3. Affixed to the cam shaft 212 is a cam element 210 having an active (or high) zone which extends clockwise from the line s to the line t. Rotatably mounted on the cam shaft is a replaceable and adjustable cam element 211 having an active zone extending clockwise from the line u to the line v. Attached to cam shaft 212 is a collar 213 which holds the adjustable cam element 211 against the main cam element 210. A bolt 208 passes through an arcuate slot 209 in the adjustable cam element and is threaded

into the main cam element. The cam roller x has a face wide enough to engage both the edge of the main cam element 210 and the adjustable cam element 211. By setting the adjustable cam element to effect various degrees of overlap of the active zones of elements 210 and 211, the effective active and inactive zones of the cam are varied.

Figs. 4 to 12 show a few of the many printing effects that may be produced by utilizing the present invention. The webs shown in these figures represent the web after it has been acted upon by the printing cylinder. For the sake of illustration, the printing cylinder is assumed to be engraved with either a square design, or a circular design, or both. Each design printed on the web is illustrated in full lines. Where a design on the printing cylinder passes the printing zone without being printed (due to pressure roller 174 being elevated), the location of such design with respect to the web is indicated in dot-dash lines in Figs. 4 to 12.

For each of Figs. 4 to 12 the printing cylinder is the same size, and cam 188 is the same though rotated at various speeds relative to the printing cylinder. In each of these figures, one printing cylinder rotation corresponds to the web length between consecutive vertical dot-dash lines. However, the location of these lines has nothing to do with the beginning and end of the printed slips (if such are being made) as the web may be so severed as to place the design on any selected part of the slip.

For Fig. 4, the control cam (188 in Fig. 1) rotates synchronously with the printing cylinder which has one square engraving. The cam action graph 188^a indicates that the web is in contact with the printing cylinder during intervals i (five shown) and out of contact during intervening intervals h . Accordingly, web 145^a is printed as shown, with one rectangle per printing cylinder rotation; and the length of the printing cylinder impression is equal to arrow 400^a, which is the peripheral length of the printing cylinder.

To print the web 145^b shown in Fig. 5 it is only necessary to so adjust the speed of cam 188 that it makes one rotation for each two rotations of the printing cylinder. In other words, the cam runs at half the angular speed of the printing cylinder. As indicated by cam graph 188^b, the design is printed only every second rotation of the printing cylinder, so that the printing cylinder impression is twice the peripheral length of the printing cylinder, as indicated by the length of arrow 400^b.

Fig. 6 shows the effect of reducing the angular speed of the cam 188 to one third that of the printing cylinder as indicated by graph 188^c. The design is printed on web 145^c only once every third rotation of the printing cylinder; and the printing cylinder impression has a length equal to arrow 400^c.

In Fig. 7 the web 145^d is printed the same as the web in Fig. 6. The printing cylinder impression has the same length as indicated by arrow 400^d. However, the result is obtained by rotating the control cam at two-thirds the angular speed of the printing cylinder, the cam action being indicated by graph 188^d.

For Figures 8 to 12, the printing cylinder has both square and circular engravings. Operated in continuous contact with the web, it would print the web 145^e shown in Fig. 8, the length of the printing cylinder impression being indicated by arrow 400^e.

If this two design cylinder is used with the cam 188 operating as for Fig. 4, it prints a web 145^f as shown in Fig. 9. This is the same as web 145^a, the circular design being blanked out by the cam action indicated by graph 188^f. The length of the impression is that of arrow 400^f.

By cutting the cam speed in half as indicated by graph 188^g, Fig. 10, the web 145^g is printed. This is the same as web 145^b, Fig. 5, the length of the printing cylinder impression being that of arrow 400^g.

For Fig 11, the cam is operated synchronously with the printing cylinder as indicated by graph 188^h. However, the phase of the cam is shifted 15 180 degrees from the condition indicated in Fig. 9. Thus, the web 145^h is printed with the circular design instead of the square design. Arrow 400^h indicates the length of the impression, which is equal to the peripheral length of the printing cylinder.

For Fig. 12, the cam 188 is slowed to half speed as indicated by graph 188ⁱ. The result is that the length of the impression is doubled as indicated by the length of arrow 400ⁱ; and web 145ⁱ is printed with the circular design every second revolution of the printing cylinder.

For these examples, it will be apparent that a variety of effects may be produced by suitably correlating the angular speeds of the control cam and printing cylinders. These may be related after the manner of ratios used in hunting tooth gear sets. Thus even with a cam speed near to the cylinder speed, the length of the impression may be made several (or even many) times the peripheral length of the printing cylinder. Also, the same cylinder may have various designs which may be printed selectively or in various chosen combinations. In parent application Serial No. 211,325, filed June 2, 1938 (now Patent No. 2,217,191, issued October 8, 1940), and also in another division thereof Serial No. 301,114, filed October 25, 1939, I have shown another press by means of which various aspects of the invention may be carried out.

45 In compliance with the patent statutes, I have disclosed the best forms in which I have contemplated applying my invention. However, it will be understood that the disclosures are illustrative and not limiting.

50 What is claimed is:

1. In the art of printing, the method of producing individual printed slips having cylinder impression lengths less than the peripheral length of the printing cylinder, which method comprises: continuously rotating the printing cylinder for a full revolution, continuously feeding a web to be printed in one direction only and in a path adjacent to said printing cylinder so that said web may be brought into printing engagement therewith, engaging the web with the cylinder at a predetermined point in the cylinder rotation, maintaining the engagement during a fraction only of the cylinder rotation, then disengaging the web from the printing cylinder and feeding a length of the web corresponding to the length of the cylinder impression on the web to a severing point, and there severing said length from the web.

2. In the art of printing, the method of printing selectively from a printing cylinder having a plurality of designs spaced about its periphery, which method comprises: continuously rotating the cylinder, passing a web adjacent to the cylinder and feeding the web independently of feed by the cylinder and in one direction only, contacting the web with the cylinder during the time

when the selected design is adjacent to the web, and disengaging the web from the cylinder during the time when any non-selected design is adjacent to the web.

3. In the art of printing, the method of printing a web with impressions longer than the peripheral length of the printing cylinder, which method comprises: rotating the cylinder, passing the web adjacent to the cylinder and feeding the web in one direction only and independently of feed by the cylinder, and alternately contacting and disengaging the web from the cylinder at a cyclic rate less than the frequency of complete cylinder rotations.

4. In the art of printing, the method of producing individual printed slips having cylinder impression lengths greater than the peripheral length of the printing cylinder, which method comprises: continuously rotating the printing cylinder, engaging a web to be printed with the cylinder at a predetermined point in the cylinder rotation, disengaging the web from the printing cylinder after a predetermined amount of rotation in contact with the web which amount of rotation is greater than one revolution of said printing cylinder, advancing a predetermined length of the web to a severing point while out of contact with the printing cylinder, and severing a slip from the printed web, the length of the slip corresponding to the length of web passing the printing cylinder and advanced to the severing point during the foregoing steps.

5. In the art of printing, a method of printing selectively from a printing cylinder having a plurality of designs spaced about its periphery, comprising continuously rotating the printing cylinder, independently feeding a web adjacent to the cylinder, contacting the web with the cylinder during that time in its continuous rotation when a selected design is adjacent to the web, and disengaging the web from the cylinder during that time in its continuous rotation when any non-selected design is adjacent to the web.

6. In the operation of a rotary printing press, a method of producing printed impressions differing in length from the peripheral length of a printing cylinder having a plurality of designs

spaced about its periphery, comprising continuously rotating the printing cylinder, feeding a web in a forward direction in juxtaposition to the rotating printing cylinder so that said web may be brought into printing engagement therewith, alternately contacting the web with the cylinder when a selected design is adjacent to the web and disengaging the web from the cylinder when a non-selected design is adjacent to the web, and feeding the web in the same forward direction while it is out of contact with the printing cylinder.

7. In the art of printing, a method of printing a web with impressions longer than the peripheral length of the printing cylinder, comprising continuously rotating the cylinder, independently feeding the web adjacent to the cylinder and in one direction only, and alternately contacting and disengaging the web from the cylinder at a cyclic rate less than the frequency of complete cylinder rotations.

8. In the art of printing, a method of printing a web with impressions a predetermined amount longer than the peripheral length of a printing cylinder having a plurality of designs spaced about its periphery, comprising continuously rotating the cylinder, feeding the web adjacent to the cylinder and independently thereof, and alternately contacting and disengaging the web from the cylinder at a cyclic rate less than the frequency of complete cylinder rotations, the web contacting the cylinder during the time in its continuous rotation when a selected design is adjacent to the web and disengaging the cylinder during the time in its continuous rotation when a non-selected design is adjacent to the web.

9. In the art of printing, a method of printing a web with impressions longer than the peripheral length of the cylinder, comprising rotating the cylinder, feeding the web adjacent to the cylinder and in one direction only, alternately contacting and disengaging the web from the cylinder at a cyclic rate less than the frequency of complete cylinder rotations, and feeding the web in the same forward direction while it is out of contact with the printing cylinder.

ADOLPH WEISS.
